Specification for Design.

Patented Aug. 20, 1918.

Application filed April 15, 1918. Serial No. 228,781. Term of patent 14 years.

To all whom it may concern:

Be it known that I, **ALBERT W. MARSHALL**, a citizen of the United States, residing at Detroit, in the county of Wayne and State of Michigan, have invented a new, original, and ornamental Design for a Lens for Auto-Headlights, of which the following is a specification, reference being had to the accompanying drawing, forming part thereof, in which—

Figure 1 is a rear elevation of the lens showing my new design;

Fig.2 is a side elevation; and
Fig. 3 is a top plan view.

I claim:—

The ornamental design for a lens for auto headlights substantially as shown.

In testimony, that I claim the foregoing as my own, and have hereto affixed my signature in the presence of two witnesses.

ALBERT W. MARSHALL.
